UNITED STATES PATENT OFFICE.

ROBERT A. RUSSELL, OF RIDGEWOOD, NEW JERSEY, ASSIGNOR TO PARAGON CAN & CAP COMPANY, INC., OF PATERSON, NEW JERSEY, A CORPORATION OF NEW YORK.

RECEPTACLE CLOSURE.

Application filed January 13, 1923. Serial No. 612,387.

This invention relates to a receptacle closure and, more particularly, to a so called screw cap for bottles and jars, such for instance, as a catsup bottle.

5 An object of the invention is to provide such an article which is designed to engage threads formed on the inside of the neck of the receptacle, and which includes effective means for establishing a substantially perfect sealing engagement between the closure 10 and the receptacle.

Another object consists in providing such a device which may be cheaply and expeditiously manufactured and which will be 15 slightly in appearance.

A further object consists in providing certain improvements in the form, construction and arrangement of the several parts whereby the above named and other objects may 20 be effectively attained.

Receptacle closures which are provided with threads designed to mate with threads formed on the inside of the neck or mouth of the receptacle have been provided with 25 rings or washers of cork, rubber composition or other yielding material, such rings or washers being arranged to lie between the top edge of the receptacle neck or mouth and a shoulder or flange formed on the closure, 30 so that the rings or washers would be compressed upon the receptacle in an axial direction, when the cap or closure was in position thereon. This construction has not proved entirely satisfactory from the point of view 35 of effecting a complete seal, largely because there was nothing comparable to a wedging action in the application of the closure to the receptacle, and also because of the difficulty of acting upon the discs or washers 40 with sufficient force to thoroughly accomplish the desired result.

Furthermore, it frequently happens that glass receptacles, such as catsup bottles, have minute cracks or fissures existing at the lip 45 or extreme edge of the neck of the receptacle, as a result of the process of manufacturing the receptacle. These cracks or fissures commonly extend inwardly about one-eighth of an inch, considered in the direction of the 50 height of the receptacle, and permit a certain amount of leakage through the part of the receptacle where they occur.

It will be clear that a ring or washer 55 which presses only upon the outer edge of the receptacle will not serve to close these

cracks or fissures and will not, therefore, accomplish an effective seal.

With these well known disadvantages in mind I have devised the present invention, a practical embodiment of which is represented in the accompanying drawings, in which—

Fig. 1 represents a detail elevation, partly in section, showing my improved closure applied to the neck of a bottle.

Fig. 2 represents a detail elevation, partly broken away showing the closure by itself.

The closure is preferably composed of sheet metal, such as sheet iron which has been coated with tin and lacquered, and consists of an upper member 1 and a lower member 2. The upper member is formed substantially in the shape of a flat cylinder and can readily be drawn from a blank of sheet metal by a die operation, in a manner 75 well understood in the art.

The lower member 2 of the closure includes a flange 3 which is interlocked with the upper member 1 by means of a folded seam 4. This seam is of conventional character and may be formed by a dieing operation which is familiar to all those skilled in this industry.

The member 2 also includes a portion which is denoted by 5 and is substantially in 85 the shape of a truncated cone, or, so to speak, tapered. This portion 5 intervenes between the flange 3 and a threaded portion 6 at the lower part of the member 2.

In manufacturing the member 2, it may 90 be drawn by a suitable die operation, with the flange 3 projecting straight out laterally and with the portion 6 substantially cylindrical in form. After the member 2 has been thus formed, the portion 6 is suitably 95 threaded by passing it between the well known threading rollers, and the flange 3 is bent into interlocking engagement with the member 1, as previously described.

The seam 4 not only serves to firmly unite 100 the members 1 and 2, but it constitutes a beading which improves the appearance of the closure and strengthens or reinforces the flange 3.

A ring or washer 7, of suitable compressible material, such as rubber compound, is fitted on the tapered portion 5 of the member 2. This washer 7 will normally be held in place by its frictional grip upon the portion 5, as indicated in Fig. 2.

The outside diameter of the tapered portion 5 is made less than the inside diameter of the neck of the receptacle at its mouth, and the outside diameter of the washer 7 is
5 made greater than the diameter of the said portion of the receptacle, so that when the closure is applied to the receptacle, denoted by 8, by screwing it therein, the washer or ring 7 enters for some distance inside of the
10 neck of the receptacle 8 so as to be clamped between the said inside portion of the neck and the tapered portion 5 of the member 2. Another part of the washer 7 rests upon the top edge of the neck of the receptacle 8 and
15 is clamped thereupon by the flange 3. This condition of the washer is clearly shown in Fig. 1.

Thus the washer 7 not only bears upon the portions of the receptacle just mentioned in order effectively to seal any cracks or fissures and to cover any irregularities in the material of which the receptacle is composed, but the said washer is forced into place by a wedging action similar to that
20 which occurs when an ordinary cork is forced into the neck of a bottle, so that a most complete and perfect sealing engagement is established.

For convenience in manual operation of
30 the closure, it is preferably provided with a knurling 9, which can be done at the same time that the portion 6 is being threaded, as is well known by operatives in this industry.

35 It will be clear that the members 1 and 2

of the closure may be formed in ways other than that hereinabove described, and that it may be desirable to subject it to an additional coating or recoating of some non-corrosive material, such as tin or lacquer, after
40 it has been formed; and I desire it to be understood that various changes may be resorted to in the material, form, construction, arrangement and method of forming the various parts without departing from the
45 spirit and scope of my invention; and that I do not intend to be limited to the details herein shown and described, except as they may be included in the claim.

What I claim is:—

50 A sheet metal receptacle closure comprising, an upper closure member, a lower closure member seamed to said upper closure member and including, a lateral shoulder adjacent said seam, a portion adjacent the
55 bottom of said lower closure member constituting means for engaging the interior of the receptacle, a tapering portion between said lateral shoulder and said receptacle engaging portion, and a compressible element 60 surrounding said tapering portion and adapted to be pressed between said shoulder and said tapering portion on the closure and the top and inner wall of the receptacle when the closure is moved toward the receptacle, thereby forming a seal.

In testimony, that I claim the foregoing as my invention, I have signed my name this twelfth day of January, 1923.

ROBERT A. RUSSELL.
